UNITED STATES PATENT OFFICE.

THOMAS WELCH, OF BRIDGEPORT, OHIO, ASSIGNOR OF ONE-HALF TO WILLIAM V. CAMPBELL, OF BRIDGEPORT, OHIO.

TRUSS.

1,157,353.

Specification of Letters Patent. Patented Oct. 19, 1915.

Application filed April 27, 1910. Serial No. 557,984.

To all whom it may concern:

Be it known that I, THOMAS WELCH, a citizen of the United States, residing at Bridgeport, in the county of Belmont and 5 State of Ohio, have invented certain new and useful Improvements in Trusses, of which the following is a specification.

My invention relates to an improvement in trusses, and the object is to provide a pad 10 which can be applied to the ruptured part, and which will have the proper effect upon the ruptured part without causing any inconvenience to the wearer.

A further object is in the provision of 15 means whereby the truss can be adjusted to suit the wearer.

The invention consists further in certain novel features of construction and combinations of parts which will be more fully described hereinafter, and pointed out in the 20 claim.

In the accompanying drawings: Figure 1 is a view in elevation, Fig. 2 is a detail, sectional view through the pad, and Fig. 3 is a 25 detail view showing the adjustment between the rear pad and the wire which is received around the body.

A, represents the wire or body portion of the truss, which is adapted to pass over the 30 point of the hip; and B, is the spiral cone-shaped pad which is formed from the body or wire A. The end of the wire projects downwardly or vertically from the center of the cone as at 1, and has a loop 2, formed 35 at the end thereof. Connected to the opposite end of the wire A is a loop or rear pad 3 which is provided with the parallel members 4, which are connected by a ferrule 5, through which the wire A passes. The 40 thumb-screw 6 is provided for connecting the loop-member at different positions upon the rod. A head 7 is formed or connected to the end of the wire A, which is provided with openings through which the parallel 45 members 4 of the loop 3 extend. Connected

to the loop member 3 is a strap or band 8, which is provided with a hook 9, which hook is adapted to engage the loop 2 in the projection 1, whereby the truss can be connected to the wearer after the proper adjustment 50 has been obtained by the thumb-screw upon the wire A. All of the strain which is used in securing the truss upon the body is received by the loop member 3, and the projection 1 of the pad B. The projection 1 relieves to a great extent the strain upon the 55 pad B, which would cause it to become unbearable to the wearer, and which at the same time insures the pad being held upon the ruptured part.

From the foregoing, it will be seen that I have provided a very simple construction of truss which will produce the results desired, and the cone-shaped formation of the pad B will allow the pad to come in contact with 60 the ruptured part. While I have only shown the truss with a single pad, it is evident that a similar pad could be applied or connected to the wire A, which would allow another pad to be brought around the body, and in 65 position upon the ruptured part.

Having fully described my invention, what I claim as new and desire to secure by Letters Patent, is:—

A truss comprising an arched wire terminating in a spiral cone-shaped pad at one 75 end, and having a flat rear pad adjustably connected with its other end, the cone-shaped pad integral with the wire, and the wire forming it extending back approximately through the axial center of the cone 80 and terminating in a loop, and a strap or band connected with the rear pad and with said loop.

In testimony whereof I affix my signature, 85 in the presence of two witnesses.

THOMAS WELCH.
